ASSIGNORS TO THE ATLANTIC REFINING COMPANY, OF PHILADELPHIA, PENN-
SYLVANIA, A CORPORATION OF PENNSYLVANIA.

PROCESS OF AND APPARATUS FOR DISTILLING PETROLEUM.

1,073,548.

Specification of Letters Patent.

Patented Sept. 16, 1913.

Application filed October 4, 1909. Serial No. 520,937.

To all whom it may concern:

Be it known that we, JOHN W. VAN DYKE and WILLIAM M. IRISH, both citizens of the United States, residing at Philadelphia, in the county of Philadelphia and State of Pennsylvania, have invented certain new and useful Improvements in Processes of and Apparatus for Distilling Petroleum, of which the following is a specification.

10 This invention relates more particularly to the distillation of petroleum in the form of undistilled residues containing all, or nearly all, the intermediate fraction in addition to the lubricant (or, when the petroleum yields paraffin wax, the lubricant and wax yielding) fraction of the petroleum, as said fractions are hereinafter defined; but it extends also to the distillation of undistilled residues resulting from a still further 15 evaporation of the crude petroleum, but containing at least forty per cent. of said lubricant (or lubricant and wax yielding) fraction; and in part the invention extends to the distillation of petroleum in other 20 forms (distillate or undistilled). Each of the improvements composing the invention is intended to be secured for all the uses to which it can be applied, with or without modification.

25 30 In the prior current practice undistilled residues of the kind herein above first mentioned have been distilled partly with a view to increasing the yield of burning oil (kerosene) by cracking decomposable hydrocarbons of the lower boiling portion of such residues and partly with a view to obtaining distillate containing the decomposable but undecomposed or only slightly decomposed hydrocarbons of the lubricant (or 35 lubricant and wax yielding) fraction of the crude oil; and the mode adopted for reconciling these to a certain extent inconsistent objects has been to subject such residues to distillation first in stills with their 40 tops exposed (fully or with slight protection only) to the atmosphere for cooling and thus partially condensing the vapors before they pass over to be condensed as distillate (the same still serving both for 45 the precedent distillation of the crude oil or of a residue thereof and for the cracking operation) and then the remaining portion 50 thereof in stills (termed tar stills) with

their tops protected for keeping the vapors hot, the residuum from the cracking operation being transferred to the tar stills with intermediate cooling, settling and storage and in the case of petroleum obtained from the oil fields of Illinois and of other petroleum of analogous character also with subjection of the residual oil to treatment with sulfuric acid or to other special treatment (in addition to settling) for separating therefrom the coke and other heavy products of the cracking operation. The extent to which the cracking operation is carried has been regulated according to the judgment of the manufacturer in view of market and other conditions. The transferred residuum or tar has sometimes contained part only of the lubricant (or lubricant and wax yielding) fraction of the crude oil and sometimes it has contained the whole of said fraction, together with a considerable portion of the intermediate fraction (as these fractions are herein defined).

The condensate which results from cooling the vapors in the exposed top stills has fallen directly into the liquid oil in distillation, or else has run down the still walls into said oil. The uncondensed portion of the so cooled vapors has then passed over and been at once condensed (except very light products) by means of a water cooled condenser. The vapors from the tar stills, on the other hand, after passing over have been subjected to a series of two partial condensations in air cooled condensers before their complete condensation (except very light products) in a water cooled condenser, each partial condensation being effected in a single large pipe inclined upward and cooled merely by exposure to the atmosphere.

At the end of a run, before opening the stills for cleaning out, it has been the practice to fill the same with free steam, in order to expel the hydrocarbon vapors therefrom; and these with the steam have been passed through the condensers employed in the distillations. When the residual petroleum has been withdrawn from said exposed top stills much matter has been left adherent to the interior of the stills; and there has thus been a direct loss (because the adherent matter is in part at least itself of value)

and also an indirect loss because time and labor are required to clean out the still after each run preparatory to the next.

The necessary cooling of the residual oil 5 in prior current practice and its storage also involve a loss of time and labor; and there is a further loss of valuable material in the matter which settles out in the storage tanks or is removed by the additional special treatment needed in the prior current practice with petroleum of the kinds obtained from the oil fields of Illinois, Kansas, Oklahoma and Texas. Moreover, with any given plant, whenever (as is often desirable) 10 the distillation in the exposed top stills has been carried farther than or not so far as the point at which no more and no less residuum is made than the tar stills have capacity to distil, a part either of the exposed top stills or of the tar stills of said plant 15 must be idle. Further, from various causes, the separation of hydrocarbons in the partial condensations of said prior current practice has been very imperfect. One cause 20 is the lack of control over the cooling effect produced on the vapors. Different installations have differed in the area and degree of exposure of the air cooled (condensing) walls, according to the views of the manufacturer; but with any given installation the cooling effect produced on the vapors has 25 been customarily controlled solely through regulation of the still fires. By slackening these, the rate of evaporation in the still can 30 be lessened; and less heat being then imparted by the vapors to the heat conducting walls, these fall in temperature and condense a larger proportion of the passing vapors (although the absolute volume condensed is smaller than before.) By urging 35 the fires, evaporation is increased; and the heat conducting walls rise in temperature and condense a smaller proportion (but more absolutely) of the evolved vapors.

40 There are, however, variable conditions in a run or in different runs, due to the varying temperature of the air or other meteorological conditions and to variations in the oil in distillation in a run or to be distilled 45 in different runs, which cannot be met as completely as would be desirable (if at all) by regulation of still fires; and, besides, it is not possible to insure a perfect regulation of them at all times. The cooling also 50 itself of the vapors has not been thorough in prior current practice; nor has proper opportunity been afforded for interchange of hydrocarbons between the condensate and the vapors.

55 Various proposals have been made for improving the separation of petroleum hydrocarbons by partial condensation of their mixed vapors; but in spite of them the prior current practice has been as stated. By reason 60 of the imperfect separation different

cuts of distillate have contained hydrocarbons which, if not positively objectionable therein, could be more advantageously utilized as constituents of other cuts. For example, hydrocarbons which are sufficiently colorless and are otherwise suited for water white burning oil (kerosene) distillate are made (as a result of imperfect separation) to pass into distillate of poorer quality; because they are accompanied by hydrocarbons too highly colored or otherwise unsuited for water white oil. In like manner the yield of lubricant stock (or of lubricant stock and wax yielding material) is diminished by imperfect separation; because this results in the first of the desired hydrocarbons being accompanied by hydrocarbons which are undesirable in such stock (or material).

65 By the aid of the present invention, the said products, for the obtainment of which the prior current practice was adopted, can be obtained without the loss of time and labor and material incident to the customary transfer of residuum in said prior current 70 practice and also without the loss in enforced idleness of part of the plant which results in prior current practice whenever the tar stills are of insufficient capacity for 75 distilling all the residuum of the desired character which can be made in the exposed top stills, or conversely are able to distil more of such residuum than the latter stills can furnish. Further, by the aid of the present 80 invention said products can be obtained of 85 better quality or in larger amount or both of better quality and in larger amount than in the prior current practice. Moreover, if 90 it should be preferred to obtain distillate 95 without so much cracked products, it is possible to do so without necessarily carrying 100 over into such distillate more than a small proportion of the lubricant (or lubricant and wax yielding) hydrocarbons.

105 In accordance with the present invention, crude petroleum is distilled, it may be in any known or suitable way, until an undistilled residue is obtained of the kind herein above mentioned; and this residue is then subjected to distillation at the requisite high 110 temperatures uninterruptedly in two stages; the earlier of which is conducted with a view to condensing out of the mixed mass of vapors for return to the oil in distillation those hydrocarbons which it is desired to 115 have in the lubricant stock (or the lubricant stock and wax yielding material) and also those hydrocarbons which it is desired to crack into lighter oil, while allowing the other hydrocarbons to pass over to be condensed as distillate and is terminated while 120 the residual oil yet represents a large part at least (not less than 25 per cent.) of the lubricant (or of the lubricant and wax yielding) fraction of the crude oil; and the later 125 130

of which stages is thereupon begun and is conducted with a view to obtaining distillate composed of the decomposable but undecomposed or only slightly decomposed hydrocarbons of said fraction, a suitable temperature difference (say of about 100° F. to 150° F. or more) for holding back the desired lubricant (or lubricant and wax yielding) hydrocarbons being maintained in said 5 earlier stage between the liquid oil in distillation and the vapors passing over to be condensed as distillate, and a less temperature difference being maintained in said later stage between them (say a difference 10 which is smaller than that of the earlier stage by 50° F., 75° F., or more). Unless otherwise preferred for special purposes, the distillation, both in the earlier and in the later of said stages, is performed under 15 atmospheric pressure, or nearly so, and without the injection of steam or other aeroform fluid into the stills. During the later of said stages the vapors in the still should be protected against conductive cooling to 20 the extent at least to which they would be subjected thereto in one of the exposed top stills of prior current practice; because such cooling would needlessly increase the fuel consumption and would provoke a wasteful 25 decomposition of hydrocarbons; and in the earlier stage it is advantageous to protect the vapors in the still against such conductive cooling and to subject them after they leave the still to the conductive cooling necessary 30 to form sufficient condensate for return to the oil in the still for reevaporation therein; because a cleaner separation of hydrocarbons can be effected outside of the still than in it.

35 In the accompanying drawings, Figures 1 and 2 taken together (with introduction of short lengths of connecting pipe) constitute a view, partly in perspective (broken away in places) and partly in vertical section, of a 40 distilling apparatus in accordance with the present invention, a series of condensers forming part of said apparatus being shown in Fig. 1 and the still in Fig. 2; Fig. 3 is a detail view of a portion of the first condenser of the series; Fig. 4 is a diagram illustrating a modified form of the same condenser; and Fig. 5 is a detail of a relief valve for a pipe in a condenser of such modified form.

45 The still *a* is shown in the form of a horizontal cylinder heated by a number of fire places whose ash pit doors show at *b*. It is protected against loss of heat externally, the protection shown consisting of blocks *c*, 50 brick-work *d* and cement *e*; and it is covered with sheet metal *f*. There is a pipe *g* for filling the still with oil and a pipe *h* for conducting away the vapors. This vapor pipe is connected with the vapor space of the 55 still *a* by means of a short upright pipe *i*

having a removable cover *k*. A side opening receives the end of the vapor pipe *h*. Below said side opening is a flap valve whose operating handle is seen at *l*; and below said valve is another side opening 70 which receives the pipe *m*, a continuation of which is formed by pipe *n* having a valve *p*. In running the flap valve is open and the valve *p* closed. At the end of a run, when steam is introduced into the still to expel the 75 vapors therefrom, their positions are reversed.

The pipe *q*, which joins the pipe *m*, is provided with a safety valve *r* and a vacuum valve *s*. A pipe *t* is provided for introducing steam into the still at the end of a run before opening the manholes *u* for cleaning out. At *w* is the chimney for the fires under the still. At *x* are holes for pipes to deliver still gases or other fuel gases 80 under the still for burning. This still *a* with its parts and appurtenances, is shown in order to illustrate by way of example a form of still which can well be used to carry the invention into effect. Other 85 known or suitable forms can be used. The still shown in Fig. 2 for volatilizing the petroleum embodies improvements in respect to its setting which form the subject of our application of October 13, 1910, No. 90 586,861.

The vapor pipe *h* leads to a condenser in the form of numerous pipes 2 arranged in parallel between header 3 and chamber 4. In Fig. 1 the vapor outlet ends of these 100 pipes are at a higher level than their vapor inlet ends; so that the condensate, which is formed in each pipe and naturally runs downward, will flow oppositely to the corresponding stream of vapors. In order to 105 equalize the flow of the vapors among these pipes, the aggregate cross section of the passages at their narrowest points is proportioned with reference to the passage of the predetermined volume of vapors per unit 110 of time under a predetermined pressure (figures found useful to be given later); and, in order that the streams may be longer exposed to cooling in pipes of given length, their average cross sections are made 115 greater than those at said narrowest points and the outlet ends of said pipe are strictured (or made smaller than said average cross section). Said strictured outlets may well constitute the narrowest points. Means 120 are provided for automatically releasing the pressure in said pipes should it become excessive at any time. The best arrangement is shown in Fig. 3, in which the strictured outlet 5 is formed in the body of a 125 light valve 6 which rests by its own weight over the end of the pipe. There may be such a valve in each of said pipes; but the pressure could, of course, be released without having so many valves. 130

While dimensions and proportions can be varied, good results have been attained for a still holding a thousand barrels of oil up to the usual level with an air cooled condenser having fifty six of the pipes 2, each eleven feet in length and four inches in external diameter (giving about 665 square feet of cooling surface on the closely approached heat conducting walls of pipes 2). A circular vapor outlet opening 5 of an inch and a quarter diameter would suffice for each pipe 2, the vapor pipe *h* having an internal diameter of twelve inches and the valves 6 weighing about thirty three ounces each.

The pipes 2 are disposed for cooling by controllable currents of the aeriform cooling fluid flowing transversely to and longitudinally of said pipes. The header 3 is 20 annular and forms part of a passage for the cooling fluid in the middle of the group of pipes 2; while the top of the chamber 4 is a circular disk and obstructs such passage at its bottom; and the pipes 2 are inclosed 25 in a casing 7 which fits around the header 3 at the top and has inlet openings 8 at the bottom for inflow of air from the surrounding atmosphere. Each inlet is provided with a valve 9, which can be opened, 30 wholly or in part, or can be completely closed, as may be desired. Air currents are produced in the casing 7 by heat absorbed from the walls of pipes 2. The vapor pipe *h* leads from the still directly to the chamber 4 in Fig. 1. This chamber is much deeper than a mere manifold or header (the depth represented being about three-fourths the length of pipes 2). It is provided with a non-conducting (or heat retaining) jacket 10. In it, resting on the grate 11, are pieces 12 of solid material, say cobble stones of four to eight inches in diameter. The condensate from pipes 2 flows down over said stones and is given 40 by them a back and forth transverse motion; while the vapors which rise upward between them are similarly deflected; and the vapors then pass into the pipes 2 for cooling conductively in distinct streams of 45 small diameter.

The vapor outlet of the air cooled partial condenser 2, 3, 4 is connected by pipe 13 with the vapor inlet of a second partial condenser 14 composed of numerous pipes 55 set between headers and exposed to the air for cooling. The vapor outlet from condenser 14 is connected by pipe 15 with a water cooled condenser, shown in the form of a coil 16 placed in a water tank 17, which 60 is supported on walls 18 and cross beams 19. Thus, as shown, the vapors from the still *a* flow successively through two partial condensers each of them cooled by aeriform fluid, and then through a water cooled 65 condenser.

The liquid outlets 20 and 21 of the partial condensers are respectively connected through U traps with the water cooled draw off pipes 22 and 23, placed in water tank 17. The water cooled draw off 22 is valved and is connected with outlet 20 by means of a cross which also serves to connect said outlet with two other valved pipes 24 and 25 respectively, pipe 24 being a draw off for condensate from the chamber 4 when said condensate becomes too thick to flow at the temperature of the water in tank 17, and pipe 25 being a run back leading to the still *a*. The pipe 24 is maintained at a higher temperature than the draw off 22. It may 70 have such higher temperature merely because exposed to the air instead of being immersed in the water of tank 17; or additional means of securing higher temperatures can be provided.

At 26 is a cover to exclude rain, in case the still stands out of doors; and the partial condenser 14 may well be similarly protected. A valved pipe 27 shown in dotted lines can be used as a run back, if desired, between the condenser 14 and the still *a*.

The vapors generated in still *a* pass by pipe *h* to chamber 4; and on reaching the top of said chamber 4 they are divided into numerous streams, one for each of the pipes 95 2. These streams flow in parallel inside the closely approached heat conducting walls of said pipes and are severally surrounded by aeriform fluid (atmospheric air) for cooling and are further equalized among 100 themselves by the stricturing which they are given at their outlets by passage through the restricted openings 5 (Fig. 3). Should the pressure become excessive, one or more of the valves 6 rise and automatically release 105 the pressure, the released vapors passing on to condenser 14. The vapors flow in opposite directions in pipes 2 to the corresponding streams of condensate formed by the cooling in the same; and a good opportunity 110 for exchange of hydrocarbons between them is thus afforded, more volatile hydrocarbons in the condensate replacing less volatile in the vapors.

The flow of the aeriform fluid transversely to and longitudinally of pipes 2 over and between the same tends to uniform and efficient cooling of the vapors. Such currents are given force and direction by their lateral confinement; while the cooling can 120 be regulated by opening and closing the valves 9. The vapors are brought into intimate contact in chamber 4 with the condensate for interchange of hydrocarbons, while they are protected against indirect 125 cooling. Useful but not so good results are obtainable without the pieces 12. The same is true with respect to the jacket on chamber 4. For a continuous complete distillation of crude petroleum in the still *a*, the 130

latter is filled with the proper charge of crude oil (say, a thousand barrels) and is heated by fires underneath; and the heating is continued until the still contents become dry or nearly so, wax tailings coming over as the last distillate. During the first part of the run the portion of the crude oil which is more volatile than the intermediate fraction as herein defined is received as distillate; while during the remainder of the run, which is conducted in two stages, the intermediate and the lubricant (or lubricant and wax yielding) fractions are distilled, the former with more and the latter with less 10 decomposition (cracking) of constituent hydrocarbons. The later of said stages would advantageously be commenced as soon as or shortly after a percentage of the crude oil equal to said more volatile portion plus said intermediate fraction has been received as distillate. During said first part of the run and the earlier of said two stages the run back 25 is open and the draw offs 22 and 24 are closed. During said later stage the run back 25 is closed and the draw offs 22 and 24 are opened one at a time, the former as long as the distillate from bottom of chamber 4 is thin enough to flow at the temperature in pipe 22, and the latter subsequently. The 20 temperature difference between the liquid oil in distillation and the vapors which have passed over to be condensed as distillate is greater in the previous distillation than in said later stage. In the former the vapors are made to flow through the partial condenser 2, 3, 4 before they pass over to be condensed as distillate, all such condensation being performed in the air cooled partial condenser 14 and in the water cooled 30 complete condenser 16 and the condensate from condenser 2, 3, 4 returning by run back 25 to the oil in distillation in still *a*; while in said later stage they are condensed as distillate as soon as they have passed out of the still *a*. Until then they are protected against conductive cooling by the non-conducting jacket *c, d, e* on the still; so that the temperature difference between the liquid oil and the vapors passing over is correspondingly small.

The total flow of distillate at any time can largely be controlled by regulating the fires; but with equal evaporation per hour the collection of distillate per hour will naturally be larger when it includes condensate from condenser 2, 3, 4 than when it does not. It is advantageous so to regulate the still fires that the total flow per hour of distillate diminishes during the distillation of part 40 at least of the intermediate fraction, as compared with the average of such flow during the distillation of the more volatile portion of the crude oil, and that the combined flow per hour from the condensers 14 and 16 (exclusive of condenser 2, 3, 4) during the dis-

tillation of part at least of the lubricant (or of the lubricant and wax yielding) fraction should equal or exceed the average of such flow during the distillation of said intermediate fraction; while the average flow of 70 distillate per hour at the same time from the condenser 2, 3, 4 may well itself exceed the same average. The flow of distillate from each condenser varies from time to time according to the nature of the oil; and the flow 75 from condenser 16 may (and perhaps always would) cease before the beginning of distillation of the intermediate fraction. If so, it should be flowing again before the close of such distillation.

During the distillation of the intermediate fraction and also of the lubricant (or of the lubricant and wax yielding) fraction the vapors are advantageously cooled in condenser 2, 3, 4 to temperatures intermediate 85 400° F. and 600° F. so that the uncondensed portion of said vapors may be as free as practical from lubricant (or lubricant and wax yielding) hydrocarbons. Any desired cuts in any distillate can be made by directing the stream to different distillate receivers in the known manner.

The air inlet valves 9 would be more nearly closed at the beginning of each run, when light hydrocarbons are being distilled, 95 and also at the end of each run when the volume of vapors is comparatively small, than they would be during the intermediate part of the run. In other words, the currents of cooling fluid are controlled to increase and decrease in a general way the cooling effect on the vapors according to the varying volume and temperature of the latter. Said air inlet valves 9 would also be closed more when the weather is cold or 100 windy and less (if at all) when it is warm or still. The valves 9 can also be manipulated to counteract or to compensate for other variables. In general observation of the streams from the respective condenser 110 outlets, with test of samples, if thought expedient should give sufficient indications.

At the end of the run the valve *p* in pipe *n* is opened and the valve *l* is turned to close the ordinary vapor pipe *h*. Steam is then 115 introduced through the pipe *t*. It fills the still *a* and expels the hydrocarbon vapors. They pass, with steam, through the pipes *m, n* to any desired place or receptacle without entering the condenser 2, 3, 4, the condenser 14, or the condenser 16; so that at the next run the first runnings of condensate are not composed in part of hydrocarbons expelled by the steam. So far as concerns the condensate from condenser 2, 3, 4, as this returns to still *a*, the presence in it of said hydrocarbons would be of small importance; and it is, therefore, of minor importance for the valve *l* and valved branch pipe *n* to be between cen- 120 125 130

denser 2, 3, 4 and the still *a*. After expulsion of hydrocarbon vapors, the steam is shut off; and the still *a* is allowed to cool, is opened, is cleaned, is closed and then receives a new charge of petroleum.

In a complete distillation of one thousand and forty six barrels of crude petroleum having a gravity of 33 6/10° B. and yielding paraffin wax the following figures have been observed and will give a good general idea by way of example of a run.

Time after bringing in the still.

15	Distillation of portion more volatile than the intermediate fraction, as shown by the liquid oil in still <i>a</i> attaining 600° F.	19 20/60 hrs.
16	Distillation of intermediate fraction, as shown by liquid oil in still <i>a</i> being above 600° F. and the condensate from condenser 2, 3, 4 having a viscosity less than 65 seconds at 100° F. by Saybolt's universal viscosimeter	18 hrs.
20.	Distillation of lubricant and wax yielding fraction, being residue after removal of intermediate fraction and lighter portion	17 hrs.
	Total	54 20/60 hrs.

Flow of distillate.

25	Distillation of portion more volatile than intermediate fraction:	
	Condenser 16, 147 barrels; condenser 14, 211 barrels	358 bbls.
	Average per hour both condensers	18 1/2 bbls.
30	Distillation of intermediate fraction:	
	Condenser 16, 15 barrels; condenser 14, 203 barrels	218 bbls.
	Average per hour both condensers	12 1/10 bbls.
35	Distillation of lubricant and wax yielding fraction:	
	Condenser 16, 64 barrels; condenser 14, 113 barrels; condenser 2, 3, 4, 257 barrels	434 bbls.
	Average per hour first two condensers	11 1/10 bbls.
	Average per hour all three condensers	27 1/10 bbls.
	Average per hour of first half of distillation from first two condensers	17 25/100 bbls.
	Average per hour of first half of distillation from all three condensers	37 1/10 bbls.

Gravities of distillates.

40	Distillation of portion more volatile than intermediate fraction:	
	Condenser 16:	
	Lightest	70 7/10° B.
	Heaviest	48 8/10° B.
	Condenser 14:	
	Lightest	63 5/10° B.
	Heaviest	40 5/10° B.
45	Distillation of intermediate fraction:	
	Condenser 16:	
	Lightest	57° B.
	Heaviest	47° B.
	Condenser 14:	
	Lightest	40 5/10° B.
	Heaviest	34 8/10° B.
50	Distillation of lubricant and wax yielding fraction:	
	Condenser 16:	
	Lightest	55 7/10° B.
	Heaviest	41° B.
	Condenser 14:	
	Lightest	37 6/10° B.
	Heaviest	28° B.
	Condenser 2, 3, 4:	
	Lightest	31° B.
	Heaviest received by water cooled pipe 22	11° B.

Temperatures after bringing in still.

60	Distillation of portion more volatile than intermediate fraction:	
	Oil in still <i>a</i> :	
	Lowest	210° F.
	Highest	600° F.
	Vapors passing over to be condensed as distillate (in header 3):	
	Lowest	168° F.
	Highest	480° F.
	Temperature difference, average	97 5/10° F.
	Vapors leaving still <i>a</i> (in pipe <i>i</i>):	
	Lowest	193° F.
	Highest	560° F.

Distillation of intermediate fraction:

65

Oil in still <i>a</i> :	
Lowest	600° F.
Highest	700° F.

Vapors passing over to be condensed as distillate (in header 3):	
Lowest	470° F.
Highest	570° F.

Temperature difference, average	151° F.
Vapors leaving still <i>a</i> (in pipe <i>i</i>):	70

Lowest	560° F.
Highest	660° F.

Distillation of lubricant and wax yielding fraction:	
Oil in still <i>a</i> :	

70

Lowest	691° F.
Highest	(See note).

75

Vapors passing over to be condensed as distillate (in pipe <i>i</i>):	
Lowest	644° F.
Highest	810° F.

80

Temperature difference, average	(See note).
Vapors after first fractional condensation as distillate (vapors in header 3):	

85

Lowest	317° F.
Highest	607° F.

90

NOTE.—By an accident the temperatures in the liquid space of still *a* were not observed at the last seven periods of hourly observation. From other experience it is estimated that the highest temperature in the liquid space in the still was about 850° F.; and (using so estimated temperatures for seven of the eighteen intended observations) the average temperature difference during the distillation of the lubricant and wax yielding fraction is estimated to have been 46° F. The average temperature difference at the eleven actual observations was 50° F.

The heating of the still was continued for three hours after the distillate ceased to flow from condensers 16 and 14 and for two hours after that from condenser 2, 3, 4 was turned into pipe 24 (wax tailings). In the last hour of flow from condenser 2, 3, 4 through pipe 22 only one barrel of distillate (gravity 11° B. at 60° F.) was received. In the hour previous half a barrel (gravity 55 7/10° B.) was received from condenser 16, one barrel (gravity 35° B.) from condenser 14, and two barrels (gravity 18 5/10° B.) from condenser 2, 3, 4.

Distillate did not flow from the condenser 16 in the distillation of the intermediate fraction during ten hours, and in the previous distillation during four hours. Distillate commenced to flow first from condenser 16 and was running two hours and twenty minutes before it commenced to flow from the draw off 23 of condenser 14. These hours of no flow in one or other condenser are taken in in estimating the average flow as given in table. More than half the distillate in the distillation of the lubricant and wax yielding fraction was received in the first six hours; and the flow during such six hours is the basis for the average flow per hour of first half of distillation of said fraction. Twelve thousand two hundred pounds of coke were removed from the still at the end of the run.

Observations were made at each hour of the clock, the first one being twenty minutes after bringing in the still. The gravities shown are those of samples taken at the times of observation. The temperatures given as lowest and as highest respectively are the lowest and highest of those so taken. The average temperature differences are the quotients from adding together the differ-

ences at the times of observation and dividing by the number of observations.

In practical working it is unnecessary to ascertain temperatures; since observation of the distillates or distillates and returning condensate will give sufficient information to an experienced stillman; but resort can be had to thermometric readings, should it be at any time desired.

10 Should it be so desired, the earlier stage of the distillation of the undistilled residue composed of the intermediate and the lubricant (or lubricant and wax yielding) fractions of the crude oil can be prolonged into 15 the distillation of the latter fraction, said stage being terminated while the desired portion, not less than twenty five per cent., of said fraction remains in the still.

Should it be desired not to conduct the 20 complete distillation of the crude oil in the still *a*, all, or any part, of the portion more volatile than the intermediate fraction can be distilled off in another still or stills in any known or suitable way; and the residual 25 oil can then be subjected to uninterrupted distillation in the still *a* in said two stages; and, if preferred for any reason, the distillation can be carried further before transfer to the still *a*, provided the residual oil 30 to be subjected to distillation uninterruptedly in said two stages shall contain at least forty per cent. of the lubricant (or of the lubricant and wax yielding) fraction of the crude oil.

35 In Fig. 4 a jacketed chamber 30 with pieces 12 of solid material loosely piled together receives the vapors from still *a* and is provided with the same run back and draw off pipes 22, 24 and 25 as the chamber

40 4. From the upper part of said chamber the vapor flows by pipe 31 into the annular header 32, which corresponds with the header 3 of Fig. 1, except that it now forms the inlet to pipes 2 instead of the outlet 45 therefrom. The vapors being made to flow downward through the pipes 2 equalize themselves among the several streams therein, without requiring the latter to be limited in their aggregate cross section; because

50 the tendency is to check the flow of vapors through the hotter pipes; but strictured outlet openings and means for releasing pressure automatically can be used, as indicated (for example) in Fig. 5; in which a valve

55 33 having a restricted opening 34 therein is upheld by the slight pressure of a spring 35. The condensate from pipes 2 falls into pan 39 and flows by pipe 40 to the perforated annular pipe 36; which distributes it

60 over the top of the loose pile of pieces 12. The vapors uncondensed in chamber 30 and pipes 2 pass through chamber 37 and pipe 38 into condenser 14; which corresponds with the similarly numbered part in Fig. 1.

65 With the arrangement of Fig. 4, during

the earlier stage of the uninterrupted distillation the vapors pass over from the lower ends of pipes 2 to be condensed as distillate; and the temperature difference between the liquid oil in distillation and such vapors would be measured by thermometers in said oil and in the vapors in the top of chamber 37 respectively.

As employed in this specification, the lubricant (or lubricant and wax yielding) fraction and the intermediate fraction taken together of any given crude petroleum are represented by the percentage by volume of said crude petroleum which remains in the still when the still's contents attain a temperature of 600° F. (or the temperature commencement of cracking in case it should be lower than 600° F.) in a distillation of

70 said crude petroleum in the ordinary way under atmospheric pressure without introduction of aeriform fluid into the still; and the lubricant (or lubricant and wax yielding) fraction is represented by the percentage by volume of said crude petroleum which remains in the still when portions of distillate from the outlet of the customary

75 water cooled condenser first exhibit either a viscosity as high as 65 seconds at 100° F. by Saybolt's universal viscosimeter or a cloud at a temperature as high as 50° F. (which-

80 ever characteristic is first exhibited) in a distillation of said crude petroleum with introduction into the liquid oil of free steam in suitable volume to prevent cracking. For

85 concordant results said distillations (or assays) must always be performed in the same manner; and they may well be performed by using such a laboratory apparatus as is shown in cut No. 1286 in the catalogue of E. H. Sargent & Company, of 145 Lake

90 street, Chicago, Illinois, for 1908. It has a copper still of cheese box form heated by a gas flame underneath; and it is provided with means for introducing free steam into

95 the liquid oil in the still. A still with a charging capacity of about ten liters would be large enough; and it should receive a charge about equal to its capacity.

100 In the distillation under atmospheric pressure without introduction of aeriform fluid into the still steam is, of course, not admitted. The heat may be so regulated that distillate is received from the condenser at the uniform rate of about eight

105 per cent. by volume per hour of the charge of crude oil. The distillate may be received in two per cent. portions; and they (or such of them as may be necessary) should be tested for flashing points by the closed cup

110 method, after removal of hydrogen sulfid, when this is present. The temperature of the oil in the still at the completion of each portion should be noted. When the flashing points begin to exhibit a progressive re-

115 cession, it will be known that substantial

120

125

130

cracking has set in; and the temperature at the completion of the portion of maximum flashing point may be taken to be the commencement of cracking. Should this temperature be below 600° F., the percentage of the crude oil then remaining in the still represents the intermediate and lubricant (or lubricant and wax yielding) fractions of the crude oil (taken together), the percentage 5 previously collected as distillate representing the more volatile portion of the same crude oil. Should this temperature of commencement of cracking be above 600° F., the percentages when the liquid oil attains 600° 10 F. are to be taken.

15 In the distillation with introduction of free steam into the liquid oil the charge of crude petroleum (as before) should correspond with the charging capacity of the 20 still; the heat may be so regulated that hydrocarbon distillate is received from the condenser at the uniform rate of about fifteen per cent. by volume per hour of the charge of crude oil; and the free steam supply 25 may be so regulated that the stream from the condenser contains water of condensation equal in volume to from a third to a half of said hydrocarbon distillate. The steam may be dry and saturated; or it 30 may be slightly superheated. The distillate may be received in two per cent. samples; and they (or such of them as may be necessary) should be tested for viscosity and (when the petroleum yields paraffin wax) 35 for cloud (paraffin wax content) also. When a portion exhibits either a viscosity as high as 65 seconds at 100° F. by Saybolt's universal viscosimeter or a cloud at a 40 temperature as high as 50° F. (whichever characteristic first appears) the undistilled residue plus said portion represents with sufficient accuracy the lubricant (or lubricant and wax yielding) fraction of the petroleum. The difference between it and the 45 percentage representing the intermediate and lubricant (or lubricant and wax yielding) fractions taken together (as shown by previously mentioned assay) represents the intermediate fraction of the crude petroleum. The portions of distillate to be tested 50 for viscosity (or viscosity and cloud) should be separated by settling and decantation from the accompanying water before they are so tested.

55 In consequence of official requirement of division, we filed two divisional applications on April 18, 1911; which have been officially numbered 621,904 and 621,905, respectively. The subject-matter of application 621,904 60 corresponds with claims 15 to 31 (both inclusive) and 36 to 60 (both inclusive) of our original specification as filed on October 4, 1909; and the subject-matter of application 621,905 corresponds with claims 32 to 35 65 (both inclusive) of the so filed specification.

Said claims numbered 15 to 60 in our so filed specification have, of course, been withdrawn from the present (parent) application in view of the aforesaid division of subject-matter.

We claim as our invention or discovery:

1. The process of distilling petroleum in a form which contains the defined lubricant (or lubricant and wax yielding) fraction of the crude petroleum to the extent of forty per cent. of said fraction as a minimum, by heating such undistilled petroleum to the temperature necessary to distil component hydrocarbons, cooling the evolved vapors first to temperatures at which a partial condensation is effected and a residue left of uncondensed vapors and then to lower temperatures for effecting condensation of such residual vapors, returning condensate from the first mentioned cooling to the oil in distillation and drawing off as distillate condensate formed by said further cooling, and so continuing until the oil in distillation has been substantially reduced in volume yet not to such extent that it contains less than twenty five per cent. by volume of said lubricant (or lubricant and wax yielding) fraction of the crude petroleum, and thereupon, while the so reduced oil contains said lubricant (or lubricant and wax yielding) fraction to the extent of twenty five per cent. of said fraction of the crude petroleum as a minimum and while the distillation is carried on uninterruptedly, cooling the vapors evolved from the so reduced oil first to temperatures at which a partial condensation is effected and a residue left of uncondensed vapors and then to lower temperatures for effecting condensation of such residual vapors and drawing off condensate formed by said partial condensation of vapors evolved from the so reduced oil and condensate formed by said further cooling of the residual vapors as distinct distillates, and continuing the distillation with such cooling of vapors and such drawing off of distillates until a substantial quantity of condensate with a viscosity as high as 65 seconds at 100° F. by Saybolt's universal viscosimeter has been collected as distillate, the last mentioned distillate being formed from vapors whose average temperature at the place where they pass over to be condensed as such distillate differs from the average contemporaneous temperature of the oil in distillation less than the average temperature of the vapors which form the first mentioned distillate in the earlier stage of the distillation at the place where they pass over to be condensed as such distillate differs from the average contemporaneous temperature of the oil in distillation in said earlier stage, substantially as described.
2. The process of distilling petroleum in a form which contains the defined lubricant

(or lubricant and wax yielding) fraction of the crude petroleum to the extent of forty per cent. of said fraction as a minimum, by heating such undistilled petroleum to temperatures above 450° F., cooling the evolved vapors to temperatures above 400° F. and more than 50° F. below the contemporaneous temperatures of the oil in distillation and then to lower temperatures, returning 5 condensate so formed above 400° F. to the oil in distillation and drawing off as distillate condensate formed by the further cooling of vapors whose temperatures are above 400° F. at the place where they pass over to 10 be condensed as such distillate, and so continuing until the oil has been substantially reduced in volume yet not to such extent that it contains less than twenty five per cent. by volume of said lubricant (or lubricant and wax yielding) fraction of the crude petroleum, and thereupon, while the so reduced oil contains said lubricant (or lubricant and wax yielding) fraction to the extent of twenty five per cent. of said fraction 15 of the crude petroleum as a minimum and while the distillation is carried on uninterruptedly, cooling the vapors evolved from the so reduced oil first to temperatures at which a partial condensation is effected and 20 a residue left of uncondensed vapors and then to lower temperatures for effecting condensation of such residual vapors and drawing off condensate formed by said partial condensation of vapors evolved from the 25 so reduced oil and condensate formed by said further cooling of the residual vapors as distinct distillates, and continuing the distillation with such cooling of vapors and such drawing off of distillates until a substantial 30 quantity of condensate with a viscosity as high as 65 seconds at 100° F. by Saybolt's universal viscosimeter has been collected as distillate, the last mentioned distillate being formed from vapors whose average 35 temperature at the place where they pass over to be condensed as such distillate differs from the average contemporaneous temperature of the oil in distillation less than the average temperature of the vapors 40 which form the first mentioned distillate in the earlier stage of the distillation at the place where they pass over to be condensed as such distillate differs from the average contemporaneous temperature of the oil in distillation in said earlier stage, substantially as described. 45

3. The process of distilling petroleum in a form which contains the defined lubricant (or lubricant and wax yielding) fraction 50 of the crude petroleum to the extent of forty per cent. of said fraction as a minimum, by heating such undistilled petroleum to the high temperatures necessary to distil hydrocarbons with boiling points above the defined temperature of commencement of 55 cracking of said crude petroleum, cooling the evolved vapors first to temperatures above 400° F. and more than 50° F. below 60

the contemporaneous temperatures of the oil in distillation and then to lower temperatures, returning condensate so formed above 400° F. to the oil in distillation and drawing off as distillate condensate formed by the further cooling of vapors whose temperatures are above 400° F. at the place where they pass over to be condensed as such distillate, and so continuing until the oil in distillation has been substantially reduced yet not to such extent that it contains less than twenty five per cent. by volume of said lubricant (or lubricant and wax yielding) fraction of the crude petroleum, and thereupon, while the so reduced oil contains said lubricant (or lubricant and wax yielding) fraction to the extent of twenty five per cent. of said fraction of the crude petroleum as a minimum and while the distillation is carried on uninterruptedly, cooling the vapors evolved from the so reduced oil first to temperatures at which a partial condensation is effected and a residue left of uncondensed vapors and then to lower temperatures for effecting condensation of such residual vapors and drawing off condensate formed by said partial condensation of vapors evolved from the so reduced oil and condensate formed by said further cooling of the residual vapors as distinct distillates, and continuing the distillation with such cooling of vapors and such drawing off of distillates until a substantial quantity of condensate with a viscosity as high as 65 seconds at 100° F. by Saybolt's universal viscosimeter has been collected as distillate, the last mentioned distillate being formed from vapors whose average temperature at the place where they pass over to be condensed as such distillate differs from the average contemporaneous temperature of the oil in distillation less than the average temperature of the vapors which form the first mentioned distillate in the earlier stage of the distillation at the place where they pass over to be condensed as such distillate differs from the average contemporaneous temperature of the oil in distillation in said earlier stage, substantially as described. 65

4. The process of distilling petroleum in the form of an undistilled residue of crude petroleum which contains the defined lubricant (or lubricant and wax yielding) fraction of said crude petroleum to the extent of forty per cent. of said fraction as a minimum, by heating such undistilled residue to the high temperatures necessary to distil hydrocarbons with boiling points above the defined temperature of commencement of cracking of said crude petroleum, cooling the evolved vapors first to temperatures above 400° F. and more than 50° F. below 70

the contemporaneous temperatures of the oil in distillation and then to lower temperatures, returning condensate so formed above 400° F. to the oil in distillation and drawing off as distillate condensate formed by the further cooling of vapors whose temperatures are above 400° F. at the place where they pass over to be condensed as such distillate, and so continuing until the oil in distillation has been substantially reduced in volume yet not to such extent that it contains less than twenty five per cent. of said lubricant. (or lubricant and wax yielding) fraction of the crude petroleum, and thereupon, while the so reduced oil contains said lubricant (or lubricant and wax yielding) fraction to the extent of twenty five per cent. of said fraction of the crude petroleum as a minimum and while the distillation is carried on uninterruptedly, cooling the vapors evolved from the so reduced oil first to temperatures at which a partial condensation is effected and a residue left of uncondensed vapors and then to lower temperatures for effecting condensation of such residual vapors and drawing off condensate formed by said partial condensation of vapors evolved from the so reduced oil and condensate formed by said further cooling of the residual vapors as distinct distillates, and continuing the distillation with such cooling of vapors and such drawing off of distillates until a substantial quantity of condensate with a viscosity as high as 65 seconds at 100° F. by Saybolt's universal viscometer has been collected as distillate, the last mentioned distillate being formed from vapors whose average temperature at the place where they pass over to be condensed as such distillate differs from the average contemporaneous temperature of the oil in distillation and then to lower temperatures and drawing off condensate formed above 400° F. and condensate formed by further cooling as distinct distillates, and continuing the distillation with such cooling of vapors and such drawing off of distillates until a substantial quantity of condensate formed above 400° F. has been collected as distillate, the last mentioned distillate being formed from vapors whose average temperature at the place where they pass over to be condensed as such distillate differs from the average contemporaneous temperature of the oil in distillation less than the average temperature of the vapors which form the first mentioned distillate in the earlier stage of the distillation at the place where they pass over to be condensed as such distillate differs from the average contemporaneous temperature of the oil in distillation in said earlier stage, substantially as described.

5. The process of distilling petroleum in a form which contains the defined lubricant (or lubricant and wax yielding) fraction of the crude petroleum to the extent of forty per cent. of said fraction as a minimum, by heating such undistilled petroleum to the temperature necessary to distil component hydrocarbons, cooling the evolved vapors first to temperatures at which a partial condensation is effected and a residue left of uncondensed vapors and then to lower temperatures for effecting condensation of such residual vapors, returning condensate from the first mentioned cooling to the oil in distillation and drawing off as distillate condensate formed by said further cooling, and so continuing until the oil in distillation has been substantially reduced in volume yet not to such extent that it contains less than twenty five per cent. by volume of said lubri-

cant (or lubricant and wax yielding) fraction of the crude petroleum, and thereupon, while the so reduced oil contains said lubricant (or lubricant and wax yielding) fraction to the extent of twenty five per cent. of said fraction of the crude petroleum as a minimum and while the distillation is carried on uninterruptedly, cooling the vapors evolved from the so reduced oil first to temperatures at which a partial condensation is effected and a residue left of uncondensed vapors and then to lower temperatures for effecting condensation of such residual vapors and drawing off condensate formed by said partial condensation of vapors evolved from the so reduced oil and condensate formed by said further cooling of the residual vapors as distinct distillates, and continuing the distillation with such cooling of vapors and such drawing off of distillates until a substantial quantity of condensate with a viscosity as high as 65 seconds at 100° F. by Saybolt's universal viscometer has been collected as distillate, the last mentioned distillate being formed from vapors whose average temperature at the place where they pass over to be condensed as such distillate differs from the average contemporaneous temperature of the oil in distillation less than the average temperature of the vapors which form the first mentioned distillate in the earlier stage of the distillation at the place where they pass over to be condensed as such distillate differs from the average contemporaneous temperature of the oil in distillation in said earlier stage, and the cooling of the vapors to form condensate returning to the oil in distillation in the earlier stage of the distillation as well as the cooling of vapors to form condensate collected as distillate in both stages being effected by passing said vapors between closely approached heat conducting surfaces after said vapors leave the vapor space of the still, substantially as described.

6. The process of distilling petroleum in a form which contains the defined lubricant (or lubricant and wax yielding) fraction of the crude petroleum to the extent of forty per cent. of said fraction as a minimum, by heating such undistilled petroleum to the temperature necessary to distil component hydrocarbons, cooling the evolved vapors first to temperatures at which a partial condensation is effected and a residue left of uncondensed vapors and then to lower temperatures for effecting condensation of such residual vapors, returning condensate from the first mentioned cooling to the oil in distillation and drawing off as distillate condensate formed by said further cooling, and so continuing until the oil in distillation has been substantially reduced in volume yet not to such extent that it contains less than twenty five per cent. by volume of said lubri-

cant (or lubricant and wax yielding) fraction of the crude petroleum, and thereupon, while the so reduced oil contains said lubricant (or lubricant and wax yielding) fraction to the extent of twenty five per cent. of said fraction of the crude petroleum as a minimum and while the distillation is carried on uninterruptedly, cooling the vapors evolved from the so reduced oil first to temperatures at which a partial condensation is effected and a residue left of uncondensed vapors and then to lower temperatures for effecting condensation of such residual vapors and drawing off condensate formed by said partial condensation of vapors evolved from the so reduced oil and condensate formed by said further cooling of the residual vapors as distinct distillates, and continuing the distillation with such cooling of vapors and such drawing off of distillates until a substantial quantity of condensate with a viscosity as high as 65 seconds at 100° F. by Saybolt's universal viscosimeter has been collected as distillate, the last mentioned distillate being formed from vapors whose average temperature at the place where they pass over to be condensed as such distillate differs from the average contemporaneous temperature of the oil in distillation less than the average temperature of the vapors which form the first mentioned distillate in the earlier stage of the distillation at the place where they pass over to be condensed as such distillate differs from the average contemporaneous temperature of the oil in distillation in said earlier stage, and the average volume of distillate received per hour being larger in the earlier part at least of said later stage than it is in said earlier stage, substantially as described.

7. The process of distilling petroleum in a form which contains the defined lubricant (or lubricant and wax yielding) fraction of the crude petroleum to the extent of forty per cent. of said fraction as a minimum, by heating such undistilled petroleum to the temperature necessary to distil component hydrocarbons, cooling the evolved vapors first to temperatures at which a partial condensation is effected and a residue left of uncondensed vapors and then to lower temperatures for effecting condensation of such residual vapors, returning condensate from the first mentioned cooling to the oil in distillation and drawing off as distillate condensate formed by said further cooling, and so continuing until the oil in distillation has been substantially reduced in volume yet not to such extent that it contains less than twenty five per cent. by volume of said lubricant (or lubricant and wax yielding) fraction of the crude petroleum, and thereupon, while the so reduced oil contains said lubricant (or lubricant and wax yielding) fraction to the extent of twenty five per cent.

of said fraction of the crude petroleum as a minimum and while the distillation is carried on uninterruptedly, cooling the vapors evolved from the so reduced oil first to temperatures at which a partial condensation is effected and a residue left of uncondensed vapors and then to lower temperatures for effecting condensation of such residual vapors and drawing off condensate formed by said partial condensation of vapors evolved from the so reduced oil and condensate formed by said further cooling of the residual vapors as distinct distillates, and continuing the distillation with such cooling of vapors and such drawing off of distillates until a substantial quantity of condensate with a viscosity as high as 65 seconds at 100° F. by Saybolt's universal viscosimeter has been collected as distillate, the last mentioned distillate being formed from vapors whose average temperature at the place where they pass over to be condensed as such distillate differs from the average contemporaneous temperature of the oil in distillation less than the average temperature of the vapors which form the first mentioned distillate in the earlier stage of the distillation at the place where they pass over to be condensed as such distillate differs from the average contemporaneous temperature of the oil in distillation in said earlier stage, and the partial condensation in one at least of the two stages of the distillation being controlled by alterations of cooling effect distinct from those produced by regulation of the still fires, substantially as described.

8. The process of distilling petroleum in a form which contains the defined lubricant (or lubricant and wax yielding) fraction of the crude petroleum to the extent of forty per cent. of said fraction as a minimum, by heating such undistilled petroleum to the temperature necessary to distil component hydrocarbons, cooling the evolved vapors first to temperatures at which a partial condensation is effected and a residue left of uncondensed vapors and then to lower temperatures for effecting condensation of such residual vapors, returning condensate from the first mentioned cooling to the oil in distillation and drawing off as distillate condensate formed by said further cooling, and so continuing until the oil in distillation has been substantially reduced in volume yet not to such extent that it contains less than twenty five per cent. by volume of said lubricant (or lubricant and wax yielding) fraction of the crude petroleum, and thereupon, while the so reduced oil contains said lubricant (or lubricant and wax yielding) fraction to the extent of twenty five per cent. of said fraction of the crude petroleum as a minimum and while the distillation is carried on uninterruptedly, cooling the

vapors evolved from the so reduced oil first to temperatures at which a partial condensation is effected and a residue left of uncondensed vapors and then to lower temperatures for effecting condensation of such residual vapors and drawing off condensate formed by said partial condensation of vapors evolved from the so reduced oil and condensate formed by said further cooling of the residual vapors as distinct distillates, and continuing the distillation with such cooling of vapors and such drawing off of distillates until a substantial quantity of condensate with a viscosity as high as 65 seconds at 100° F. by Saybolt's universal viscosimeter has been collected as distillate, the last mentioned distillate being formed from vapors whose average temperature at the place where they pass over to be condensed as such distillate differs from the average contemporaneous temperature of the oil in distillation less than the average temperature of the vapors which form the first mentioned distillate in the earlier stage of the distillation at the place where they pass over to be condensed as such distillate differs from the average contemporaneous temperature of the oil in distillation in said earlier stage, and the condensate formed by the partial condensation of vapors in one at least of the two stages of the distillation being brought into intimate contact with the vapors for interchange of hydrocarbons, substantially as described.

9. The process of distilling petroleum in a form which contains the defined lubricant (or lubricant and wax yielding) fraction of the crude petroleum to the extent of forty per cent. of said fraction as a minimum, by heating such undistilled petroleum to the temperature necessary to distil component hydrocarbons, cooling the evolved vapors first to temperatures at which a partial condensation is effected and a residue left of uncondensed vapors and then to lower temperatures for effecting condensation of such residual vapors, returning condensate from the first mentioned cooling to the oil in distillation and drawing off as distillate condensate formed by said further cooling, and so continuing until the oil in distillation has been substantially reduced in volume yet not to such extent that it contains less than twenty five per cent. by volume of said lubricant (or lubricant and wax yielding) fraction of the crude petroleum, and thereupon, while the so reduced oil contains said lubricant (or lubricant and wax yielding) fraction to the extent of twenty five per cent. of said fraction of the crude petroleum as a minimum and while the distillation is carried on uninterruptedly, cooling the vapors evolved from the so reduced oil first to temperatures at which a partial condensation is effected and a resi-

due left of uncondensed vapors and then to lower temperatures for effecting condensation of such residual vapors and drawing off condensate formed by said partial condensation of vapors evolved from the so reduced oil and condensate formed by said further cooling of the residual vapors as distinct distillates, and continuing the distillation with such cooling of vapors and such drawing off of distillates until a substantial quantity of condensate with a viscosity as high as 65 seconds at 100° F. by Saybolt's universal viscosimeter has been collected as distillate, the last mentioned distillate being formed from vapors whose average temperature at the place where they pass over to be condensed as such distillate differs from the average contemporaneous temperature of the oil in distillation less than the average temperature of the vapors which form the first mentioned distillate in the earlier stage of the distillation at the place where they pass over to be condensed as such distillate differs from the average contemporaneous temperature of the oil in distillation in said earlier stage, and distillation with condensation of the evolved vapors and with collection of resulting condensate as distillate being continued until condensate as heavy as the equivalent of 10° B. at 60° F. has been so collected, substantially as described.

10. The process of distilling petroleum in a form which contains the defined lubricant (or lubricant and wax yielding) fraction of the crude petroleum to the extent of forty per cent. of said fraction as a minimum, by heating such undistilled petroleum to the temperature necessary to distil component hydrocarbons, cooling the evolved vapors first to temperatures at which a partial condensation is effected and a residue left of uncondensed vapors and then to lower temperatures for effecting condensation of such residual vapors, returning condensate from the first mentioned cooling to the oil in distillation and drawing off as distillate condensate formed by said further cooling, and so continuing until the oil in distillation has been substantially reduced in volume yet not to such extent that it contains less than twenty five per cent. by volume of said lubricant (or lubricant and wax yielding) fraction of the crude petroleum, and thereupon, while the so reduced oil contains said lubricant (or lubricant and wax yielding) fraction to the extent of twenty five per cent. of said fraction of the crude petroleum as a minimum and while the distillation is carried on uninterruptedly, cooling the vapors evolved from the so reduced oil first to temperatures at which a partial condensation is effected and a residue left of uncondensed vapors and then to lower temperatures for effecting condensation of such

residual vapors and drawing off condensate formed by said partial condensation of vapors evolved from the so reduced oil and condensate formed by said further cooling 5 of the residual vapors as distinct distillates, and continuing the distillation with such cooling of vapors and such drawing off of distillates until a substantial quantity of condensate with a viscosity as high as 65 10 seconds at 100° F. by Saybolt's universal viscosimeter has been collected as distillate, the last mentioned distillate being formed from vapors whose average temperature at the place where they pass over to be condensed 15 as such distillate differs from the average contemporaneous temperature of the oil in distillation less than the average temperature of the vapors which form the first mentioned distillate in the earlier 20 stage of the distillation at the place where they pass over to be condensed as such distillate differs from the average contemporaneous temperature of the oil in distillation in said earlier stage, and the cooling 25 of the vapors to form condensate returning to the oil in distillation in the earlier stage of the distillation as well as the cooling of the vapors to form condensate withdrawn as distillate in the later stage being performed 30 by dividing the body of vapors evolved in the still into numerous streams separated from each other by heat conducting walls and causing currents of aeriform fluid to flow over said walls transversely to 35 and between said streams of vapors, substantially as described.

11. The process of distilling petroleum in a form which contains the defined lubricant (or lubricant and wax yielding) fraction of 40 the crude petroleum to the extent of forty per cent. of said fraction as a minimum, by heating such undistilled petroleum to the temperature necessary to distil component hydrocarbons, cooling the evolved vapors 45 first to temperatures at which a partial condensation is effected and a residue left of uncondensed vapors and then to lower temperatures for effecting condensation of such residual vapors, returning condensate from 50 the first mentioned cooling to the oil in distillation and drawing off as distillate condensate formed by said further cooling, and so continuing until the oil in distillation has been substantially reduced in volume 55 yet not to such extent that it contains less than twenty five per cent. by volume of said lubricant (or lubricant and wax yielding) fraction of the crude petroleum, and thereupon, while the so reduced oil contains 60 said lubricant (or lubricant and wax yielding) fraction to the extent of twenty five per cent. of said fraction of the crude petroleum as a minimum and while the distillation is carried on uninterruptedly, cooling the vapors evolved from the so reduced oil first 65

to temperatures at which a partial condensation is effected and a residue left of uncondensed vapors and then to lower temperatures for effecting condensation of such residual vapors and drawing off condensate 70 formed by said partial condensation of vapors evolved from the so reduced oil and condensate formed by said further cooling of the residual vapors as distinct distillates, and continuing the distillation with such cooling of vapors and such drawing off of distillates until a substantial quantity of condensate with a viscosity as high as 65 seconds at 100° F. by Saybolt's universal viscosimeter has 75 been collected as distillate, the last mentioned distillate being formed from vapors whose average temperature at the place where they pass over to be condensed as such distillate differs from the average 80 contemporaneous temperature of the oil in distillation less than the average temperature of the vapors which form the first mentioned distillate in the earlier stage of the distillation at the place where they pass over to be condensed as such distillate differs from the average contemporaneous temperature of the oil in distillation in said earlier stage, and a number of condensates being 85 formed in both stages by successive coolings 90 of the vapors by means of aeriform fluid and also a condensate by cooling the residual vapors by means of a liquid, substantially as described.

12. The process of distilling petroleum 100 in a form which contains the defined lubricant (or lubricant and wax yielding) fraction of the crude petroleum to the extent of forty per cent. of said fraction as a minimum, by heating such undistilled petroleum 105 to the temperature necessary to distil component hydrocarbons, cooling the evolved vapors first to temperatures at which a partial condensation is effected and a residue left of uncondensed vapors and then to 110 lower temperatures for effecting condensation of such residual vapors, returning condensate from the first mentioned cooling to the oil in distillation and drawing off as distillate condensate formed by said further 115 cooling, and so continuing until the oil in distillation has been substantially reduced in volume yet not to such extent that it contains less than twenty five per cent. by volume of said lubricant (or lubricant and wax 120 yielding) fraction of the crude petroleum, and thereupon, while the so reduced oil contains said lubricant (or lubricant and wax yielding) fraction to the extent of twenty five per cent. of said fraction of the crude 125 petroleum as a minimum and while the distillation is carried on uninterruptedly, cooling the vapors evolved from the so reduced oil first to temperatures at which a partial condensation is effected and a residue 130

left of uncondensed vapors and then to lower temperatures for effecting condensation of such residual vapors and drawing off condensate formed by said partial condensation of vapors evolved from the so reduced oil and condensate formed by said further cooling of the residual vapors as distinct distillates, and continuing the distillation with such cooling of vapors and such drawing off of distillates until a substantial quantity of condensate with a viscosity as high as 65 seconds at 100° F. by Saybolt's universal viscosimeter has been collected as distillate, the last mentioned distillate being formed from vapors whose average temperature at the place where they pass over to be condensed as such distillate differs from the average contemporaneous temperature of the oil in distillation less than the average temperature of the vapors which form the first mentioned distillate in the earlier stage of the distillation at the place where they pass over to be condensed as such distillate differs from the average contemporaneous temperature of the oil in distillation in said earlier stage, the cooling of the vapors to form condensate returning to the oil in distillation in the earlier stage of the distillation as well as the cooling of vapors to form condensate of the specified viscosity collected as distillate in the later stage being effected by means of aeriform fluid, and the condensate of the specified viscosity collected as distillate toward the end of the distillation being drawn off through a pipe of higher temperature than the pipe through which such condensate has previously been drawn off, substantially as described.

13. The process of distilling petroleum in a form which contains the defined lubricant (or lubricant and wax yielding) fraction of the crude petroleum to the extent of forty per cent. of said fraction as a minimum, by heating such undistilled petroleum to the temperature necessary to distil component hydrocarbons, cooling the evolved vapors first to temperatures at which a partial condensation is effected and a residue left of uncondensed vapors and then to lower temperatures for effecting condensation of such residual vapors, returning condensate from the first mentioned cooling to the oil in distillation and drawing off as distillate condensate formed by said further cooling, and so continuing until the oil in distillation has been substantially reduced in volume yet not to such extent that it contains less than twenty five per cent. by volume of said lubricant (or lubricant and wax yielding) fraction of the crude petroleum, and thereupon, while the so reduced oil contains said lubricant (or lubricant and wax yielding) fraction to the extent of twenty five per cent. of said fraction of the crude petroleum as a minimum and while the distillation is car-

ried on uninterruptedly, cooling the vapors evolved from the so reduced oil first to temperatures at which a partial condensation is effected and a residue left of uncondensed vapors and then to lower temperatures for effecting condensation of such residual vapors and drawing off condensate formed by said partial condensation of vapors evolved from the so reduced oil and condensate formed by said further cooling of the residual vapors as distinct distillates, and continuing the distillation with such cooling of vapors and such drawing off of distillates until a substantial quantity of condensate with a viscosity as high as 65 seconds at 100° F. by Saybolt's universal viscosimeter has been collected as distillate, the last mentioned distillate being formed from vapors whose average temperature at the place where they pass over to be condensed as such distillate differs from the average contemporaneous temperature of the oil in distillation less than the average temperature of the vapors which form the first mentioned distillate in the earlier stage of the distillation at the place where they pass over to be condensed as such distillate differs from the average contemporaneous temperature of the oil in distillation in said earlier stage, and the condensate of the specified viscosity collected as distillate toward the end of the distillation being drawn off through a pipe of higher temperature than the pipe through which such condensate has previously been drawn off, substantially as described.

14. Apparatus for distilling petroleum in a form which contains the defined lubricant (or lubricant and wax yielding) fraction of the crude petroleum to the extent of forty per cent. of said fraction as a minimum in order to obtain distillate with a viscosity as high as 65 seconds at 100° F. by Saybolt's universal viscosimeter as well as distillate of lower viscosity, which apparatus consists of a still, a number of sets of condensing appliances which are cooled by means of aeriform fluid and are arranged in series so that one set communicates with the vapor space of the still and delivers its residual vapors to the next in series, devices for returning condensate from one set at least of said condensing appliances to said still, devices for drawing off condensate from each set of said condensing appliances as distillate, and condensing appliances for receiving residual vapors from previously mentioned condensing appliances arranged to be cooled by means of a liquid, substantially as described.

15. Apparatus for distilling petroleum in a form which contains the defined lubricant (or lubricant and wax yielding) fraction of the crude petroleum to the extent of forty per cent. of said fraction as a minimum in

order to obtain distillate with a viscosity as high as 65 seconds at 100° F. by Saybolt's universal viscosimeter as well as distillate of lower viscosity, which apparatus consists 5 of a still, condensing appliances which are cooled by means of aeriform fluid and which communicate with the vapor space of said still, devices for returning condensate from such condensing appliances to said still, two sets of devices for drawing off condensate as distillate from such condensing appliances arranged to be maintained one set at a higher temperature than the other set, and condensing appliances for receiving and 10 cooling residual vapors from previously mentioned condensing appliances, substantially as described.

16. Apparatus for distilling petroleum in a form which contains the defined lubricant 20 (or lubricant and wax yielding) fraction of the crude petroleum to the extent of forty per cent. of said fraction as a minimum in order to obtain distillate with a viscosity as

high as 65 seconds at 100° F. by Saybolt's universal viscosimeter as well as distillate 25 of lower viscosity, which apparatus consists of a still, condensing appliances communicating with the vapor space of said still, devices for returning condensate from such condensing appliances to said still, two sets 30 of devices for drawing off condensate as distillate from such condensing appliances arranged to be maintained one set at a higher 35 temperature than the other set, and condensing appliances for receiving and cooling residual vapors from previously mentioned condensing appliances, substantially as described.

In testimony whereof we have signed our names to this specification in the presence of 40 two subscribing witnesses.

JOHN W. VAN DYKE.
